UNITED STATES PATENT OFFICE

GEORGE R. SMITH, OF PHOENIX, ARIZONA

DESIGN FOR AN AUTOMOBILE RADIATOR CAP

Application filed February 20, 1929. Serial No. 30,144. Term of patent 3½ years.

To all whom it may concern:

Be it known that I GEORGE R. SMITH, a citizen of the United States of America, residing at Phoenix, county of Maricopa, and State of Arizona, have invented a new, original, and ornamental Design for an Automobile Radiator Cap, of which the following is a specification, reference being had to the accompanying drawings, forming a part thereof.

In the drawings—

Figure 1 is a side elevation of an automobile radiator cap showing my new design; Figure 2 is a view in front elevation; and Figure 3 is a top plan view.

I claim:

The ornamental design for an automobile radiator cap, as shown.

GEORGE R. SMITH.
